UNITED STATES PATENT OFFICE.

JOHN T. GIDCUMB, OF DALLAS, TEXAS.

RAILROAD CATTLE-GUARD.

1,254,322.

Specification of Letters Patent. Patented Jan. 22, 1918.

Application filed September 1, 1917. Serial No. 189,379.

To all whom it may concern:

Be it known that I, JOHN T. GIDCUMB, a citizen of the United States, residing at Dallas, in the county of Dallas and State 5 of Texas, have invented a new and useful Railroad Cattle-Guard, of which the following is a specification.

This invention relates to a new and useful improved form of railroad cattle guard to be 10 used in connection with the intersection of a railroad and highway or country road in order to prevent live stock, such as cows or horses, which may be upon the highway road from entering upon the track or rail- 15 way property. An object of the invention is to provide a form of cattle guard which may be used to safeguard a railroad company from liability losses due to the killing of animals on the tracks, and to save the ani- 20 mal's death due to fast running trains.

A further object of the invention is to provide a form of pivotal gate normally arranged parallel with the track, and adapted to pivot across said track when an animal 25 attempts to pass through the opening where this device will be installed between the highway and the track.

With the above and other objects in view the invention has relation to a certain com- 30 bination and arrangement of parts, an example of which is described in the following specification, pointed out in the appended claims and illustrated in the accompanying drawings; wherein,

35 Figure 1 is a perspective view of the cattle guard.

Fig. 2 is a sectional view of the cattle guard taken parallel with the rails of the track.

40 Fig. 3 is a detailed view of parts of the device.

Fig. 4 is a detail in plan view of certain parts.

Fig. 5 is a sectional view taken trans- 45 versely of the rails.

Referring now more in particular to the drawings, wherein the same parts throughout are designated by identical reference characters, the numeral 1 points out the rails 50 of the track mounted in the usual way upon suitable ties or supports. Treadle platforms 2 have one end pivotally supported upon a cross tie 3 and retained in position by pins 4 passed through an enlarged opening in the 55 platform and driven into the tie. The other

ends of the treadle platforms are free to undergo slight displacement up and down about the supported end as a pivotal point. The forward ends of the platforms lie free of any supporting means other than that 60 which is hereinafter explained. A shaft 5 is arranged under the track and platforms transversely thereto, said shaft being square in cross section but provided with suitable journals 6 at the point where it is passed 65 through and supported by the beams 7. A plurality of arms 8 are fixed upon the shaft and provided with an arcuate extremity 9 which lies in contact with the underneath side of the platform. The arms 8 are positioned upon the shaft at an angle with the platform so that pressure from weight exerted upon the platform will cause the arms 70 to be depressed and the shaft rotated a partial revolution. An upturned arm 10 is in- 75 tegrally formed with the shaft and provided with a connecting eye 11.

A gate comprising several parallel members 12 with an integral vertical supporting standard 13 is pivoted in a substantial 80 base 14 adjacent to track, and provided with suitable braces 15 which connect at the upper end of the standard to hold the gate in position as it revolves. An arm 16 is fixed to the standard and provided with an eye 85 on the extremity thereof for connection with the other parts. A link 17 is connected with the arm 16 and passes through the eye 11 of the arm 10 and provided with a T head 18. This confines the connecting link in the eye 90 11 and limits the action one way, which permits the rod to slide through the eye the other way. A post or standard 19 is fixed to the ground to limit the swinging action of the gate. A tension spring 20 connects 95 with the post and with the arm 16 in such a way as to normally retain the gate against the post.

The assembly and arrangement of parts establishes a direct pivotal control by the 100 treadle platforms over the swinging gate in such a manner that when an animal attempts to pass over the platform the weight thereof will cause the gate to quickly swing about and across the track against the animal 105 effectively closing the passage thereto. A cow or horse in crossing the obstacle, such as the treadle platforms offer, will hesitate in going upon it when it begins to move downwardly or depress under its weight and 110

will probably jump back, but if the animal is insistent upon going on the gate goes around with sufficient force to strike it such a blow as will cause the animal to withdraw.

5 A dotted line position A indicates the gate across the track. After the animal has backed off the depressed platform the gate will return to its normal position through the influence of the spring 20. But if for 10 any reason the gate should hang or remain in that position, or should be locked there by placing a rock or other weight on the platform by irresponsible people then a train approaching the gate would pass through 15 without material damage thereto because of the particular arrangement of the connecting link 17 and arm 10. The gate would move into a position B as indicated by dotted lines, since the connecting rod 17 20 would slip through the eye 11. This would cause a still greater tension to be placed upon the spring 20 which would immediately return the gate to its normal position after the train had passed through.

25 The treadle platforms will be constructed of steel and provided with upturned points integrally formed by a punching or stamping operation. This form of treadle platform offers a considerable obstacle to the 30 foot of the animal and will cause hesitation before attempting to tread upon it. The gate will be so installed at the road's intersection that the outer extremity of the gate will be pointed away from the road and 35 down the track. This arrangement further places the free or movable end of the treadle platform adjacent to the road.

Copies of this patent may be obtained for five cents each, by addressing the "Commissioner of Patents, Washington, D. C."

If desired, a framework 21 may be arranged upon either side of the platform to join the device with the fence inclosing the track.

The invention is presented to include all such changes and modifications in design or form which may come within the purview of the following claims.

Claims:

1. In a cattle guard gate, the combination with a platform pivotally supported at one end and freely movable at the other, of a gate adapted to swing across the track, connections between the platform and the gate to swing the latter when the platform is depressed, means for returning said gate to a normal position, and means for permitting the gate to swing on beyond its cross track position oppositely to its normal position.

2. In a stock guard gate for use on railroad crossing, a pivotal gate arranged adjacent to a railroad track, treadle platforms placed in the track and having one supported extremity with the other end movable, a shaft journaled transversely of said platform, arcuate arms fixed to the shaft and engaging the platform, an arm formed on the shaft, an arm fixed to the gate, a link 65 slidably connecting said arm on the gate and said arm on the shaft, with a head formed on the link to permit the gate to move beyond its cross track position, and a coil spring for returning said gate to its original position.

In testimony whereof I hereunto affix my name.

JOHN T. GIDCUMB.
